UNITED STATES PATENT OFFICE.

FRED B. SEEBERGER, OF PHILADELPHIA, PENNSYLVANIA.

CUE TIP AND MANUFACTURE THEREOF.

Application filed February 11, 1926. Serial No. 87,679.

The object of my invention is to provide a finished cue tip and a simple inexpensive method of making such cue tips.

A further object of my invention is to eliminate the manufacturing defects in commercial cue tips, in such manner as to retain the natural resilient playing qualities of the leather from which they are made.

Another object of my invention is to provide finished cue tips in a multiplicity of standard sizes, ready to be adhesively attached to the cue points, thereby eliminating the hand labor necessary in the preparation of ordinary commercial cue tips for play.

The improvement claimed is hereinafter fully set forth.

Cue tips, having a flat top, or semi-ovoid shape, have been well known for many years. Such cue tips have, in the past, been made in a lathe, the punched cylindrical tip blank being forced upon a knife blade mandrel, the point of which nearly penetrates to the playing surface of the cue tip. The object of this penetration is to stiffen the leather sufficiently to enable the operator to turn it to the desired shape with a hand tool. This treatment of the cue tip blank has the tendency to disrupt the fibres of the leather, thereby destroying much of the life, usefulness, and playing qualities of the cue tip.

These commercial tips are then subjected to pressure in a vise, or are flattened by pounding them with a hammer, the object being to make them firm, particularly in the center of the playing surface, and to prevent further expansion of the cue tip while in play. After being attached to the cue point, the surplus leather is cut away with a knife flush with the side of the cue point and the playing surface is shaped ready for use with sand-paper. Considerable skill and labor is required to secure the desired result.

According to my invention, I overcome the difficulties heretofore enumerated by first subjecting the flat stock to compression under a convex face punch. This operation is performed in screw or drop press, wherein a pressure suitable to the material used may be secured and applied. By these means, I compress the fibres of the stock to its maximum density in the axial center of the playing surface, and at the same time crowd the surplus leather radially from the axial center of the embryo tip blank; leaving the outer edges of the tip comparatively soft.

It is well known in the art that leather cue tip stock is not of uniform density, and that each tip blank must be separately treated. Following the foregoing operation, I proceed to cut to shape and completely sever the cue tip blank from the stock in a single operation; said blank now containing the maximum amount of material through the axial center of the playing surface. Cue tip blanks made by the above method, from properly selected material of sufficient thickness, are of uniform height, diameter, and decrease in density radially from the axial center of the tip blank.

The cue tip blank, which is cut about five-thousandths of an inch smaller in diameter than the inside walls of the die, is now subjected to yielding compression of sufficient degree, to reduce it to a desirable playing height, and to further compress the playing surface upon the body of the tip. Tips made by my method may be used immediately upon being adhesively attached to the cue point, the further labor being necessary to prepare the cue tip for playing.

The reduction of labor in the preparation of cue tips, effects a material and substantial reduction in the first cost of tipping cues, and the subsequent cost of maintaining cues in playing condition, by reason of the superior wearing qualities of cue tips made by my method.

In the accompanying drawings: Figure 1, is a side view, in elevation, of a tip cutting machine adapted to the practice of my invention; Fig. 2, a side view in elevation, of a tip cutter; Fig. 3, a detail bottom view of Fig. 2; Fig. 4, a top plan view of the cutter carrier; Fig. 5, a sectional view taken on the line *a-a* in Fig. 4; Fig. 6, a perspective view of a strip of tip stock; Fig. 7, illustrates the first step in my method of making a cue tip; Fig. 8, illustrates the second and final steps in making a cue tip blank; Fig. 9, is a side elevation of a cue tip blank; Fig. 10, illustrates a simple form of compression mechanism, partly in section, and; Fig. 11, is a side elevation of a finished cue tip.

In the practice of my invention, I select tip stock of the thickness necessary to make the desired height and diameter of a specific size cue tip blank. This stock may be of a single thickness of leather, or may have a prepared leather backing adhesively attached to the grain side thereof. I have found it very desirable to interpose a non-

yielding fabric, such as linen crinoline, or similar material, between the leather backing and the tip stock, particularly when using what is known in the art as *tete de veaux*, and which stock has the tendency to stretch freely. When using chrome leather, or other comparatively non-yielding material for the body of the tip, the backing member may be dispensed with, as may 10 the fabric, when the backing member is of fibre or material of like character.

The stock is then subjected to compression by a punch, 1, which firmly compresses the stock in the axial center of the embryo tip blank, thereby crowding the fibres downward upon the body of the stock and radially from the axial center of the blank, and increasing its density through the axial center thereof. The prepared stock, 21, is then placed in the 20 cutting machine, and is held in position by the clamp, 2, pivoted by means of a stud, 3. The clamp, 2, is depressed by a foot lever (not shown) connected to the bar, 4, at one of its ends, the other end of the bar, 4, 25 being connected to the clamp lever, 2^a, at the point, 5. The cutter, 6, which is secured in the drill press spindle, 22, is forced downward upon the stock by the hand lever, 7, which lever operates and controls the up 30 and down movement of the drill press spindle, forcing both the inside cutter, 6, and the outside cutter, 8, into the stock, 21, to a point that does not quite sever the tip blank from the stock.

35 The outside cutter, 8, is not secured in the spindle, 22, but, is disposed in the carrier, 9, which carrier is pivotally suspended in the lever, 13, by means of cone point set screws oppositely disposed in the lever, 13, as 40 shown at point, 10, and entering into the recesses, 11, and 12, provided in the carrier, 9. The supporting bar, 14, is attached to the spindle bearing, 15, and locked into position by the clamp screw, 28. The link, 16, provides a hinged connection between the bar, 14, and the carrier lever, 13, at its rear end. The front end of the lever, 13, is supported by the spring, 17, thereby keeping the carrier, 9, against the face of the spindle while 50 in operation.

When the tip blank has been completely shaped by the inside cutter, 6, the outside cutter, 8, which is rotated by being operatively engaged with the cutter, 6, by means 55 of a pin, 18, disposed in the cutter, 6, and the slot, 19, in the cutter, 8, is then depressed by means of the lever, 13, forcing the cutter, 8, through the stock, 21, and completely separating the tip blank, 25, from 60 the body of the stock. The rod, 23, is hooked in an eye bolt, 24, disposed in the lever, 13, and controls the cutting depth of the outside cutter, 8, by means of a nut, 20.

65 Fig. 10 illustrates a simple form of yield-

ing compression mechanism, suitable for compressing the cue tip blank, 25. The tip blank, 25, is placed in a well known form of cylindrical die, 1^a, disposed in the die holder, 2^a, which holder is secured to the press bed, 3^a, by means of the cap screws, 29, and 30. The flat face plunger, 4^a, is disposed in the press ram, 9^a, and forces the tip blank, 25, inside the walls of the die, 1^a, and downward upon the concave face of the plunger, 6^a, depressing the ejecting block, 7^a, and thereby bringing into action the full force of the compression spring, 14^a. The ejecting block, 7^a, is disposed upon the main compression spring retainer, 10^a, and secured in axial 75 line with the plunger, 6^a, by means of a stud, 11^a, passing through the spring retainer, 10^a, and is secured by screw threads in the ejecting block, 7^a. The head, 12^a, of the stud, 11^a, prevents the upward movement of 80 the ejecting block, 7^a, beyond a predetermined distance when actuated by the spring, 8^a, the force of the spring, 8^a, being merely sufficient to eject the tip from the die, 1^a, when finished.

The main pressure for compression is secured by means of a helical square thread spring, 14^a, which is reduced to about six-tenths of its original length by means of the bolts, 15^a, and 16^a, which pass through the spring retainer, 10^a, and are permanently secured at their bottom ends in the spring retainer, 17^a. The pressure of the spring, 14^a, may be increased or decreased by tightening or loosening the nuts, 18^a, and 19^a, on 100 the bolts, 15^a, and 16^a. The guide bars, 20^a, and 21^a, are disposed between the supporting bar, 22^a, and the under side of the press bed, 3^a, and secured in position by the bolts, 23^a, and 24^a, passing through the bar, 22^a, and secured by male threads into the press bed, 3^a. The spring retainers, 10^a, and 17^a, are provided with suitable recesses to engage the guide bars, 20^a, and 21^a, 105 and may be adjusted to the proper height 110 by means of the set screw, 26^a, disposed in the bar, 22^a, and secured in position by the lock nut, 31^a.

The advantages of my invention in the manufacture of cue tips will be obvious to 115 those skilled in the art, and to those consumers of cue tips that have been accustomed to preparing the standard commercial article by the present method of preparing such cue tips for play.

I claim as my invention and desire to 120 secure by Letters Patent:

1. The improvement in the manufacture of cue tips which consists in taking a block of suitable resilient material having opposite plane surfaces; compressing the embryo cue tip through its axial center upon the opposite plane bottom of the stock; and subsequently cutting therefrom a cue tip blank that, by such treatment, will decrease 130

in density radially from the axial center thereof.

2. The improvement in the manufacture of cue tips which consists in taking a block of suitable resilient material having opposite plane surfaces; compressing the embryo cue tip through its axial center upon the opposite plane bottom of the stock; subsequently cutting therefrom a cue tip blank that, by such treatment, will decrease in density radially from the axial center thereof; and subjecting the cue tip blank to a sufficient degree of yielding compression to produce a finished cue tip of the desired height and diameter.

3. The improvement in the manufacture of cue tip blanks which consists in taking a block of suitable resilient material having a backing disk adhesively attached thereto compressing the cue tip through its axial center upon the bottom of the stock; and subsequently cutting the finished cue tip blank therefrom.

4. The improvement in the manufacture of a finished cue tip which consists in taking a block of suitable resilient material having a backing disk adhesively attached thereto and compressing the cue tip through its axial center upon the bottom of the stock; subsequently cutting the finished cue tip blank therefrom; and subjecting the cue tip blank to a sufficient degree of yielding compression to produce a finished cue tip of the desired height and diameter.

5. The improvement in the manufacture of cue tip blanks which consists in taking a block of suitable resilient material having a leather backing disk adhesively attached thereto and a non-yielding fabric interposed between the backing disk and the body of the stock; compressing the cue tip through its axial center upon the opposite plane bottom of the stock; and subsequently cutting the finished cue tip blank therefrom.

6. The improvement in the manufacture of a finished cue tip which consists in taking a block of suitable resilient material

having a leather backing disk adhesively attached thereto and a non-yielding fabric interposed between the backing disk and the body of the stock; compressing the cue tip through its axial center upon the opposite plane bottom of the stock; subsequently cutting the finished cue tip blank therefrom; and subjecting the cue tip blank to a sufficient degree of yielding compression to produce a finished cue tip of the desired height and diameter.

7. As a new article of manufacture, a cue tip of resilient material having a leather backing disk adhesively attached thereto and a non-yielding fabric interposed between the backing disk and the body of the tip; and a substantially semi-spherical body portion opposite a plane bottom and decreasing in density radially from the axial center of the cue tip.

8. As a new article of manufacture, a finished cue tip of resilient material having a backing disk adhesively attached thereto and a non-yielding fabric interposed between the backing disk and the body of the tip; and a substantially cylindrical body portion having a convexed playing surface opposite a plane bottom and decreasing in density radially from the axial center of the cue tip.

9. As a new article of manufacture, a finished cue tip of resilient material having a backing disk adhesively attached thereto, and a substantially cylindrical body portion having a convex playing surface opposite a plane bottom, and the characteristic of decreasing in density radially from the axial center of the cue tip.

10. As a new article of manufacture, a finished cue tip of resilient material having a substantially cylindrical body portion, a convex playing surface opposite a plane bottom, and the characteristic of decreasing in density radially from the axial center of the cue tip.

FRED B. SEEBERGER.
